UNITED STATES PATENT OFFICE

2,448,972

INTERNAL-COMBUSTION ENGINE
(TURBINE TYPE)

Edward W. Gixara, Amsterdam, N. Y.

Application October 20, 1944, Serial No. 559,591

3 Claims. (Cl. 60—41)

1

This invention relates to internal combustion engines and has for its object to provide a centrifugal feed turbine.

Another object of the invention is to provide a turbine in which combustion is continuous as long as the engine is in operation.

Another object of the invention is to provide a turbine in which all of the operating elements thereof are in one integral or fixed part.

A further object of the invention is to provide a turbine engine in which the casing, the propulsion vanes, the combustion chamber, the gas deflector, the air intake and distributor are fixedly mounted upon a driven power shaft and revolve therewith.

Another object of the invention is to provide an internal combustion turbine the entire periphery of which forms an exhaust port.

A still further object of the invention is to provide in a turbine a large number of spaced vanes and means whereby pressure may be brought simultaneously upon all of said vanes.

Other features and advantages become more readily apparent from the following description and the accompanying drawings in which:

Figure 1 is a top plan view of my improved turbine,

Figure 2 is an end elevational view thereof,

Figure 3 is a sectional view taken on line 3—3 of Figure 1, and

Figure 4 is a vertical sectional view taken on line 4—4 of Figure 1.

Like reference characters indicate like parts throughout the following specifications and in several views in the drawings in which 10 indicates my turbine and 11 and 12 are spaced apart bearings, the heads 13 and 14 of which support the power shaft 15. To the free end 16 of said shaft is affixed a power takeoff pulley 17.

Integrally or fixedly carried on end 18 of shaft 15 is a rotor 19, formed of a pair of inverted substantially W-shaped (in cross section) casing members 20 and 21, integrally connected by arcuate spaced apart vanes 22, which in elevation are fan shaped. The inner reduced ends 23, of these vanes terminate at a substantially cylindrical, angular combustion chamber 24. Inwardly of said combustion chamber is another series of arcuate vanes 25, integrally formed on, or connecting the wall 20 and baffle 28. These latter vanes at their larger and inner ends 26, terminate in an atmospheric air inlet 27, at the center of the wall 21.

A substantially concave cone shaped baffle plate 28, is fixed to the inner end 26, of the shaft 15

2

and spaced lightly from the similarly formed portion 30 of the member 20, whereby an angular passage-way 31 is formed between said parts 20 and 30 and having an annular outlet 32 into the combustion chamber 24. The passageway 31 is connected by a bore 33, extending transversely through the inner end of shaft 15, and connects with the longitudinal bore 34, running substantially through said shaft 15, and to the gas inlet chamber 35, formed in the arm 36, which is an integral extension of the member 12. The part 37 of shaft 15 which passes through arm 36 and chamber 35 is provided with a peripheral groove 38, connected by a port 39 with bore 34, whereby gas from feed pipe 40 to chamber 35 enters the bore 34.

Threaded in the outer wall portion 41 of the combustion chamber 24 is a spark plug 42, the point 43 of which is adapted to engage the contact 44 supported on a bracket 45, attached to the base 46, upon which the members 11 and 12 are supported. An electric wire 47 conducts current to the contact 44.

In operation the turbine is very simple. It is first to be noted that the rotor which includes the side walls 20 and 21, the driving vanes 22 and the baffle 28, the air intake vanes 25 and the shaft 15 with its pulley 17, are all formed into one single movable unit, no other elements of the invention move. To start the turbine it is only necessary to revolve said unit until spark plug 42 engages, that is brushes, the contact 44, causing a spark in the plug gap within the combustion chamber 24, thus igniting the gas and air mixture therein. The expansion of the gas presses upon all of the arcuate vanes 22 at one and the same time and during said expansion period forces its way to escape through the passages 48, separating the vanes, and in doing so presses upon the concave surfaces of the vanes, thus driving the rotor. The rotation of the turbine draws gas into every part of the circular combustion chamber 24 through centrifugal action, and at the same time the fan formed by vanes 25 draws in atmospheric air through port 27 and drives it with force into the combustion chamber, thus forcedly mixing the air with the incoming gas from inlet 32. After the turbine has once started the firing is continuous, no further electric spark being required as the fresh incoming gases are ignited by fire already in the chamber.

As there is just one movable unit with only two bearings lost motion is reduced to the very minimum, friction is reduced to a minimum

and for the same reason and also due to the further fact that the elements of the moving unit are all integrally or fixedly connected, wear is also reduced to a minimum. Due to the construction and operation of the device, power, smooth running and life of the turbine is increased to a maximum and cost of running and upkeep is reduced. Due to the free escapement of the products of combustion vibration and noise is practically eliminated.

It is thought that persons skilled in the art to which this invention relates will be able to obtain a clear understanding of the invention after considering the description in connection with the drawing. Therefore, a more lengthy description is regarded as unnecessary.

Minor changes in shape, size and rearrangement of details and parts, such as come within the purview of the invention claimed, may be resorted to in actual practice, if desired.

Having described my invention, that which I claim as new and desire to secure by Letters Patent is:

1. A rotor all elements of which are integrally connected including a series of spaced vanes and means whereby pressure is simultaneously brought to bear upon all of said vanes, means whereby exhaust is provided for between each pair of said vanes, means whereby a fuel is fed to the rotor by centrifugal action, a combustion chamber formed in the rotor, a fan formed in the rotor, said chamber being located between the fan and the vanes, said chamber being substantially cylindrical in cross section and ring shaped, means for admitting air to the center of the fan, means for initial ignition of fluid in said chamber.

2. A turbine formed of one piece including a casing, a series of drive vanes, a suction fan, a baffle plate, a shaft and a gas inlet all formed in one single unit, said casing comprising a pair

5 of spaced walls, said vanes connecting said walls, said baffle plate fan and one of said walls being connected, a circular combustion chamber formed by said walls, and surrounding said fan, said vanes surrounding said combustion chamber, said baffle plate and one of the walls forming a circular gas feed space inlet to the combustion chamber.

10 3. A turbine formed of one piece including a casing, a series of drive vanes, a suction fan, a baffle plate, a shaft and a gas inlet all formed in one single unit, said casing comprising a pair of spaced walls, said vanes connecting said walls, said baffle plate fan and one of said walls being connected, a circular combustion chamber formed by said walls, and surrounding said fan, said vanes surrounding said combustion chamber, said baffle plate and one of the walls forming a circular gas feed space inlet to the combustion chamber, said shaft being tubular and providing 15 a gas conduit to said feed space.

EDWARD W. GIZARA.
